UNITED STATES PATENT OFFICE.

MATTHIAS BROCK, OF BOSTON, MASSACHUSETTS, ASSIGNOR TO THE MCKAY
& COPELAND LASTING MACHINE COMPANY, OF PORTLAND, MAINE.

LASTING-MACHINE.

SPECIFICATION forming part of Letters Patent No. 371,816, dated October 18, 1887.

Application filed June 6, 1887. Serial No. 240,427. (No model.)

To all whom it may concern:

Be it known that I, MATTHIAS BROCK, of Boston, county of Suffolk, and State of Massachusetts, have invented an Improvement in 5 Lasting-Machines, of which the following description, in connection with the accompanying drawings, is a specification, like letters on the drawings representing like parts.

In the lasting-machine described in United States Patent No. 203,156, dated September 17, 1878, and upon which this invention is an improvement, the toe-wiper had a movement parallel to the bolt, which serves as a pivot for the cam employed to actuate the toe-wiper; but such plan for moving the toe-wiper has in practice been found objectionable, especially when the last employed has an overhanging toe, for with only the movement stated the toe-wiper cannot act to lay the upper close to 15 the edge of the bottom of the last or close to what may be termed the "corner" of the last, or that part of the last between the bottom on which the inner sole lies and the toe part of the last.

20 My invention has for its object to so pivot and actuate the toe-wiper carrier and toe-wiper that the latter in its rising movement will hug close to and move, as it were, about or around the overhanging toe.

25 My invention consists, essentially, in the combination, with a last having an overhanging toe and toe-rest, of a toe-wiper adapted to move transversely across the overhanging toe of the last and then inwardly from the said toe toward the bottom of the last, the said toe-wiper coming in contact with the top of the overhanging toe and following its contour from that point to the edge of the last at the junction of the overhanging toe and the bottom 30 of the last, as will be described.

35 Figure 1, in vertical section and elevation, shows a sufficient portion of a lasting-machine, which, taken in connection with the machine described in United States Patent No. 208,156, will enable my present invention to be understood. Fig. 2 is a detail, looking at the face 40 of the slide, upon which is mounted the toe-wiper carrier, the said figure also showing part of the oscillating plate and carriage or plate-holder. Fig. 3 shows the toe-wiper carrier removed. Fig. 4 is a rear side elevation

of the toe-wiper carrier, the clamping-pin for holding the toe-wiper being in position. Fig. 5 shows the toe-wiper by itself; Fig. 6, a view of the toe of the last. Fig. 7 is a section 55 of Fig. 4 on the line $x-x$; and Fig. 8 is a view of the mechanism, looking toward the face of the wiper, with the toe-rest and last removed.

The toe-rest a , the rod a^1 , upon which it is pivoted, the cam a^1 , the block B' , abutment B , downhold C , toe-wiper D , oscillating plate G , cam disk or hub D' , shown as grooved at its periphery and at its upper and lower sides, the carriage or plate-holder H , the connecting-slide d^2 , its roller or other stud to enter the 60 groove at the periphery of the cam disk or hub D' , the short rod d^4 , and screw g^3 are all substantially as in the patent referred to, wherein like letters are employed to designate like parts, so that the same need not be herein 65 further specifically described.

The oscillating plate G is attached to the carriage or plate-holder H by the screw g^3 , referred to, and a depending portion, as g^4 , of the said plate-holder H is dovetailed, as best 70 shown in Fig. 2, to receive in it a slide-plate, 2, which is connected by the stud d^4 to the connecting-slide d^2 , so that as the cam or hub D' is rotated the said groove at its periphery receiving the roller-stud is made to move the 80 connecting-slide d^2 up and down, the latter causing the slide-plate 2 to be moved in the dovetailed portion g^4 of the plate-holder H .

The slide-plate 2 has two ears, as 3, between which is placed a lug, 4, of a toe-wiper carrier, c , the said lug being pivoted between the said ears by a suitable pin or pivot, 8. The toe-wiper carrier is grooved, as shown in Figs. 3 and 4, to receive the shank 6 of the toe-wiper D , composed, preferably, of two leaves, 90 20, of spring-steel, and a lining, 22, which may be of metal, as brass, or of leather, rawhide, or other usual material, the said shank being provided with a hole, 7, through which is inserted a pivot-pin, 8, the latter also being extended through holes 9 in the toe-wiper carrier. The toe-wiper carrier c at its rear side has suitable ears, between which, by a pivot-screw, 10, is mounted a cam, f , made adjustable by means of an adjusting device, (shown 100 as a screw,) 13, so that the said cam may be made to occupy a position more or less inclined

with relation to the rear side of the said carrier.

The oscillating plate G has at its front side (see Fig. 2) suitable ears, 15, between which 5 is placed a roller, 16, against which the said cam f strikes as the slide-plate 2 is raised, as described, which results in causing the toe-wiper to move not only vertically or across the highest part of the overhanging toe of the 10 last, but also diagonally forward while in contact with the overhanging toe of the last, and along that part of the overhanging toe from the highest part to the edge formed by the junction of the overhanging toe with the 15 bottom of the last, thereby enabling the toe-wiper to wipe the upper from the top of the toe of the last completely around the toe, or from the highest point, 24, of the toe of the last to the corner or edge line, 25, of the bottom 20 of the last upon which the inner sole rests, the upper being held firmly by the toe-wiper closely against the entire toe part of the last between the parts 24 and 25.

As herein shown, the pivotal point of the 25 toe-wiper carrier is nearly in line with the toe of the last, and the movement of the toe-wiper is upward and backward toward the shank of the last.

I believe myself to be the first to invent devices whereby the toe-wiper is given a movement from the highest part, as 24, of the toe of the last backwardly along and in the line of the inclined surface between the points 24 and 25, said intermediate surface constituting the 30 under side of the overhanging portion of the toe of the last. So I do not desire or intend to limit my invention to the exact devices shown to move the toe-wiper in the direction indicated, as the said devices might be otherwise 35 constructed and yet be within the scope of my 40 invention. The last L may be supported by a

heel-pin, as in the said patent, or in other usual manner.

I claim—

1. In a lasting-machine employing a last having an overhanging toe, as described, the combination, with the said last, of a toe-wiper and means, substantially as described, to actuate it to cause the said toe-wiper to travel transversely across the toe from the overhanging portion thereof to the junction of the toe with the bottom of the last, as set forth. 45

2. In a lasting-machine, a toe-rest, a toe-wiper, a carrier therefor, and a slide-plate upon which the carrier is pivoted, and with 50 means to move the said slide-plate longitudinally, substantially as set forth. 55

3. In a lasting-machine, a toe-rest, a toe-wiper, a carrier therefor, a slide-plate upon which the toe-wiper is pivoted, combined with 60 a cam to effect the movement of the toe-wiper transversely across the end of the toe of the last backward along the overhanging toe of the last to the edge of the bottom of the last, substantially as described. 65

4. In a lasting-machine, a toe-rest, a toe-wiper, a carrier therefor, and a slide-plate upon which the toe-wiper is pivoted, combined with a cam to effect the movement of the toe-wiper from the end of the toe of the last backward 70 along the overhanging toe of the last to the edge of the bottom of the last, and with means to adjust the said cam, substantially as described. 75

In testimony whereof I have signed my name to this specification in the presence of two subscribing witnesses.

MATTHIAS BROCK.
